CLAIM

The ornamental design for a control panel with keypad, as shown and described.

DESCRIPTION

FIG. 1 shows a front perspective view of a control panel with keypad.

FIG. 2 shows a front elevation view of the control panel with keypad.

FIG. 3 shows a top view of the control panel with keypad.

FIG. 4 shows a bottom view of the control panel with keypad.

FIG. 5 shows a left side view of the control panel with keypad.

FIG. 6 shows a right side view of the control panel with keypad; and,

FIG. 7 shows a rear elevation view of the control panel with keypad.

The broken lines in the figures depict portions of the control panel with keypad that form no part of the claimed design.
